United States Patent Office.

JOHN MILLER, JR., OF MARSHALLTOWN, IOWA

Letters Patent No. 108,927, dated November 1, 1870; reissue No. 4,283, dated February 28, 1871.

IMPROVEMENT IN LOCK-NUTS.

The Schedule referred to in these Letters Patent and making part of the same.

To all whom it may concern:

Be it known that I, JOHN MILLER, Jr., of Marshalltown, Marshall county, State of Iowa, have invented certain new and useful Improvements in "Nut-Locks;" and do hereby declare that the following is a full, clear, and exact description thereof, reference being had to the accompanying drawing and to the letters marked thereon making a part of this specification, in which—

Figure 1 represents a side view of two sections of a railroad track, showing the elongated metal strip attached to the fish-plate;

Figures 2 and 3 represent an end view and detached bolt showing my nut-lock; and

Figures 4 and 5 represent similar views of a modification of the same.

The nature of my invention consists in a novel manner of locking the nut upon the end of the bolt, as will be more fully hereinafter described.

A A in the annexed drawing represent the section of a railroad track.

B B represent the fish-joints, both being of the usual construction.

Upon the exterior of the fish-joint B is secured an elongated metal bar, a, which is convex on its outer face, as shown in figs. 1, 2, and 4.

C represents the bolt which passes through the fish-pieces B B and rails A, as well as through the bar a.

This bolt is made in the usual form, excepting that a cavity is formed in the under side of the head D to receive a rubber or other spring, E, as shown in fig. 3, or I use, immediately under the head of the bolt C, a recessed washer, F, inclosing said spring E.

I represents the nut which secures the bolt. This nut is grooved or made concave on its inner side, so as to snugly fit the convexity of the metal bar a.

The operation of my invention is substantially as follows:

The rubber spring being in the head D or in the washer F, the bolt C, in the latter case, is passed through the washer F, then through the usual openings in the fish-pieces B B and the rails A, as well as the plate a. The nut I is then screwed on the end of the bolt tightly, compressing the spring, and clasping itself against the convex-plate a, making a substantial lock. By my invention the nut cannot work itself loose from the bolt by jarring or otherwise.

My nut-lock is applied to the usual form of fish-pieces in common use. I add, or form with one of the fish-pieces, an elongated rib, and use a bolt having a recessed head inclosing a spring, or immediately under the head of the bolt a recessed washer inclosing a spring.

The nut I use has two concave grooves crossing each other at right angles, and which fit over the convex rib.

I am aware that a nut-lock composed of a bolt with a convex under surface, of head and convex nut, with two concave spring fish-pieces countersunk around the holes where the bolt passes, for the head and nut to fit in, is not new; hence I disclaim such to be any part of my invention.

Having thus fully described my invention, What I claim as new, and desire to secure by Letters Patent, is—

The combination of the elongated plate a convex on its outer surface, the bolt C, and nut I concave on its inner surface, and the spring E, substantially as and for the purpose hereinbefore set forth.
